UNITED STATES PATENT OFFICE.

SWITS CONDÉ, OF OSWEGO, NEW YORK.

DESIGN FOR A KNIT FABRIC.

SPECIFICATION forming part of Design No. 14,004, dated June 26, 1883.

Application filed April 25, 1883. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

This design consists in a novel arrangement of rings produced in knit fabric, said rings being disposed in parallel rows, and each ring being provided with projections on opposite sides, as fully shown in the accompanying drawing, wherein—

A represents the rings arranged in parallel rows, and c c denote the projections on opposite sides of said rings.

What I claim is—

The design for knitted fabric, consisting of rings A A, arranged in parallel rows, and having projections c c on opposite sides, substantially as described and shown. 20

In testimony whereof I have hereunto signed my name and affixed my seal, in the presence of two attesting witnesses, at Oswego, in the county of Oswego, in the State of New York, this 3d day of April, 1883. 25

SWITS CONDÉ. [L. S.]

Witnesses:

EDU MAXWELL,
JOSEPH J. REGAN.
